UNITED STATES PATENT OFFICE.

EDWIN B. THORNHILL, OF HURLEY, NEW MEXICO.

PROCESS OF PRODUCING SPONGE IRON.

Application filed January 8, 1920. Serial No. 350,171.

To all whom it may concern:

Be it known that I, EDWIN B. THORNHILL, a citizen of the United States, residing at Hurley, in the county of Grant and State 5 of New Mexico, have invented certain new and useful Improvements in Processes of Producing Sponge Iron, of which the following is a specification.

This invention relates to improvements in 10 process for producing sponge iron.

In the concentration of copper, for example, where leaching operations are conducted, it has been found that sponge iron, preferably in comminuted form, is highly 15 advantageous in producing what I term amorphous copper in the shape of a flocculent precipitate.

My present invention relates to the process 20 of obtaining this sponge iron from the ore in which it naturally occurs or from artificial iron compounds, such as Fe_2O_3 , similar to hematite and obtained by calcining or pre-roasting of iron ores in which the iron occurs in various compounds, such as sid- 25 erite, limonite, etc. I also contemplate the use of calcined iron pyrite and magnetite and hematite in its natural condition.

In some instances I find it desirable to pre- 30 heat the natural substances, as well as those which I may calcine, in order to expedite the carrying out of my process and reduce the expense thereof.

My process consists briefly in the heating 35 to the desired temperature in retorts of the iron bearing constituent mixed with the necessary proportion of a reducing agent, such as coal, hydrocarbon oils, or the like, together with an excess of carbonaceous material, such as coke, semicoke, as I term it, 40 which will be defined hereinbelow, or other materials, which is not utilized to reduce the iron bearing constituent, but is utilized to prevent cohesion of the sponge iron particles resulting from the reduction. The iron at 45 the time of its conversion from the compound, in which it occurs, to the pure sponge state will not combine with the excess of carbonaceous material referred to and the latter serves as a diluent in that it prevents 50 agglomeration of this sponge iron and enables the user of my process to obtain the pure sponge iron, which is far superior to an agglomerated product, even though the latter may be of pure iron, since I have

found that the sponge iron is far superior 55 in copper concentrating processes to an agglomerated or sintered product, use of which would result in the settling of cement or metallic copper in contradistinction to the amorphous copper described above. 60 After reduction of the iron bearing constituent in my process, the same is allowed to cool in a neutral or reducing atmosphere to a point below that at which oxidation readily occurs and the diluent material and 65 sponge iron is thereafter removed from the cooling receptacle and the iron particles separated from the remainder of the discharged product by means of a magnetic separator, or the like, which separates the diluent and 70 other non-iron material from the sponge iron so that I may not only retain the iron, but also the semi-coke or coke for re-use as a diluent.

In the accompanying drawings, I have 75 shown apparatus to carry out or effect my process. In the drawings like numerals refer to like elements.

Fig. 1 is a vertical section through the furnace of my apparatus, portions of the 80 retorts therein being shown as broken away and other portions of the apparatus being shown in elevation.

Fig. 2 is a transverse horizontal section along the line 2—2 of Fig. 1. 85

Fig. 3 is a similar section along the line 3—3 of Fig. 1.

In the drawings 10 designates generally the casing forming a part of the furnace 90 generally and having a chimney 10^a extending upwardly therefrom. Located at the bottom of the furnace 10 is the grate 10^b of conventional construction, the fire box formed by such grate being in communication with the casing 10 by means of a passage 10^c, see Fig. 1. Located within the casing 10 and spaced therefrom and from each other are the vertical retorts 11, these retorts being for convenience composed of the sections 11^a, each section being provided with a seat or socket for the interfitting end of the next section above. I have shown these retort sections as constructed of refractory material, preferably carbonaceous refractory material, as carborundum, or the like, and having a carbon lining, such as graphite, indicated by numeral 11^b, see 100 Fig. 2.

One purpose of this retort construction is to prevent the adherence of the sponge iron to the sides of the retort. Horizontal baffles 12 are located at suitable points within the casing 10, these baffles being supported upon the ledges 10^a of the furnace 10 and extending partially across the interior thereof in such wise as to form staggered circulation openings 10^b. A bottom plate 13 extends across the entire area of the furnace thereby sealing the chamber 10^c of the furnace from passage of the heating gases therethrough, this chamber being open at 10^c to the outside atmosphere and constituting a cooling chamber, it being maintained at a temperature greatly below that of the heating portion of the furnace. The heating gases flow from the fire box through the opening 10^c and thereafter circulate around the retorts 11 until they finally flow out through the chimney 10^a, such flow being caused also by the closing of the top of the furnace 10 by a cover plate 14. A rotatable damper 15 is provided in the chimney 10^a to control the flow of gas therethrough.

Located in the cooling chamber 10^c are the cooling receptacles 16 preferably constructed of cast iron, or the like, to insure rapid radiation and conduction of the heat from the reduced material. These receptacles are in communication with the interior of the retorts, as shown in the drawings, and are located above the collection hopper 17 into which their contents may be discharged by proper actuation of the slides or gates 17^a having engageable handles or portions 17^b. The hopper 17 has the outwardly engaging discharge duct 18 and a screw conveyor 19 is rotatably mounted in the hopper 17 and duct 18, being provided with a central shaft 19^a hollow to permit circulation of cooling fluid, such as water, therethrough, the same being supplied to one end by the tube 20 and discharged at the other end through the tube 21. A suitable gear 22 is mounted on the shaft 19^a and is rotated by the pinion 23 carried on the shaft 24 and rotated by a suitable motor 25, or the like. The discharge pipe is provided with the outlet 18^a. Located beneath the discharge 18^a is the belt 26 and the magnetic separating unit comprising the drive pulley 27 and drum or cobber 28 provided with suitable magnets 29 excited by means of current from a source 30 from which lead the feed wires 31, for example. In the operation of this separator, as is well known, the iron particles will be retained on the surface of the drum 28 a sufficient period of travel to insure their deposit in the collection space 45, while the non-iron particles will be projected a sufficient distance to be deposited in the collection space 50.

In the carrying out of my process, as de-

scribed above, in actual practice I have mixed three parts of magnetite with one part of Gallup coal, the latter being a coal obtained from the vicinity of Gallup, New Mexico, being technically known as non-coking coal and possessing a relatively large proportion of volatile hydrocarbons, this coal acting as a reducing agent. In addition, I added two parts of what I term "semi-coke" to operate as diluent, these proportions being by weight. The semi-coke, as I term it, is a species of coke, obtained as the result of the heating treatment of the Gallup coal mentioned above, although the coal at the conclusion of the treatment, during which the volatile constituents have been driven off, does not resemble coke in appearance, texture, or the like. These ingredients are fed into the hoppers 40, assuming the furnace to have been in operation, and are fed vertically downwardly through the retorts during which passage the heat, being maintained at the proper degree, will reduce the iron bearing constituent, i. e., Gallup coal compounds with the oxygen of the iron compound leaving the iron in the form of sponge iron, as I term it, which settling into the receptacles 16 will be rapidly cooled therein and since the latter are so located and constructed that substantially no oxygen will reach the interior thereof from the outside atmosphere, a neutral or reducing atmosphere is maintained in such receptacles. In the latter, the iron is cooled to a point below that at which oxidation will readily take place and at proper intervals of time the gates 17^a may be actuated to deposit charges of the material into the hopper 17 from which the same is fed by the screw conveyor 19 to the separator belt 26, additional cooling being obtained in the hopper during the discharge of the product by means of rotation and the cooling effect of the water cooled conveyor. As will be obvious, the magnetic separator in a well known manner will separate the principal sponge iron from the other material, which latter will, for the most part, be the so-called semi-coke or actual coke, which I am able to re-use as a diluent in the carrying out of this process.

It is to be noted that I do not wish to restrict myself to these specific ingredients, but contemplate the use of any suitable reducing medium and any suitable carbonaceous diluent, such as coke, or the like.

As explained above, the diluent is inert in so far as the carrying out of the process is concerned and serves to prevent agglomeration of the iron particles when they are at the heat of reduction, at which time a less sufficient quantity of carbonaceous material is present, such agglomeration will take place.

It will be obvious that by proper regula-

tion and operation of the apparatus described my process may be carried on continuously in contrast to the use of retorts which must be charged, cooled and dis-
5 charged intermittently.

It will also be obvious that my process is susceptible to numerous modifications and improvements and I do not wish to be restricted to the same as described and shown
10 herewith except as defined in the appended claim, nor do I wish to be restricted to the specific form of apparatus described and shown for the carrying out of my process.

What I claim is:—

A process of the class described consisting 15 in mixing iron ore with a reducing agent, thereafter passing the same through a carbon lined retort externally heated to maintain a reducing atmosphere in said retort, then cooling the reduced iron in a non-oxi-
20 dizing atmosphere, and separating the iron from the non-iron material.

In testimony whereof, I have subscribed my name.

EDWIN B. THORNHILL.
